UNITED STATES PATENT OFFICE.

HORACE SEE, OF NEW YORK, N. Y.

DESIGN FOR A CRANK.

SPECIFICATION forming part of Design No. 32,196, dated February 6, 1900.

Application filed December 29, 1899. Serial No. 742,000. Term of patent 14 years.

To all whom it may concern:

Be it known that I, HORACE SEE, of the city, county, and State of New York, have invented and produced a new and original Design 5 for Cranks, of which the following is a specification.

In the accompanying drawings, Figures 1 and 2 are respectively elevations of my design, taken from points of view relatively at 10 right angles.

My design exhibits a cylindrical portion A, at one end of which and disposed at right angles thereto is the substantially triangular plate or arm B. Extending from said plate

and on the side opposite to that from which 15 the cylindrical portion A protrudes is a short cylindrical portion C. The cylindrical portion A and the cylindrical portion C are relatively located near to two angles of the triangular plate B. In the body of said plate 20 appears a quadrangular opening D.

I claim—

The design for a crank substantially as shown and described.

HORACE SEE.
